UNITED STATES PATENT OFFICE

99,750

DESIGN FOR A GLASS BOTTLE

William E. Mackelfresh, Jr., Chicago, Ill., assignor to Ball Brothers Company, Muncie, Ind., a corporation of Indiana

Application October 15, 1935, Serial No. 59,002

Term of patent 14 years

To all whom it may concern:

Be it known that I, William E. Mackelfresh, Jr., a citizen of the United States, residing at Chicago, in the county of Cook and State of Illinois, have invented a new, original, and ornamental Design for a Glass Bottle, of which the following is a specification, reference being had to the accompanying drawing, forming part thereof.

In the drawing:—

Fig. 1 is a front elevation of a glass bottle embodying my new design, the rear face of said bottle being plain; and

Fig. 2 is a side elevation, the opposite side being similar.

I claim:—

The ornamental design for a glass bottle, as shown and described.

In testimony that I claim the foregoing as my own, I have hereunto affixed my signature.

W.M. E. MACKELFRESH, JR.
